(57) **CLAIM**

The ornamental design for a lint trap oval container, as shown and described.

DESCRIPTION

FIG. 1 is an upper perspective view of the lint trap oval container showing my design;

FIG. 2 is an end view thereof;

FIG. 3 is a side view thereof, the opposite side being a mirror image thereof;

FIG. 4 is an opposite end view thereof;

FIG. 5 is a top plan view thereof;

FIG. 6 is a bottom plan view thereof; and,

FIG. 7 is a cross-section view of FIG. 2, taken along line 7-7, thereof.

The broken lines showing of liquid in FIG. 7 is included for illustrating the environmental matter of the lint trap oval container, and forms no part of the claimed design.
